C. A. SCHMITT

LOCK FOR SLIDING DOORS

Filed Dec. 23, 1922

Inventor

C. A. Schmitt

By Watson E. Coleman
Attorney

UNITED STATES PATENT OFFICE.

CHARLES A. SCHMITT, OF ANACONDA, MONTANA, ASSIGNOR OF ONE-FOURTH TO JOHN E. EASTMAN, JR., OF ANACONDA, MONTANA.

LOCK FOR SLIDING DOORS.

Application filed December 23, 1922. Serial No. 608,697.

To all whom it may concern:

Be it known that I, CHARLES A. SCHMITT, a citizen of the United States, residing at Anaconda, in the county of Deerlodge and 5 State of Montana, have invented certain new and useful Improvements in Locks for Sliding Doors, of which the following is a specification, reference being had to the accompanying drawings.

10 This invention relates to improvements in locks for sliding doors, and more particularly to a lock for use with the sliding doors of freight cars.

An important object of the invention is 15 to provide a device of this character which may be readily attached to a freight car and which is so constructed that the door may be closed without locking the lock whenever so desired.

20 A further object of the invention is to provide a lock for sliding doors having a manually slideable bolt which when in withdrawn position is out of engagement with the locking part proper so that the door may 25 be closed when desired without locking the same.

A still further object of the invention is 30 to provide a lock having means whereby a seal may be applied to the door when so desired which seal may be broken without unlocking the lock.

These and other objects I attain by the construction and arrangement shown in the accompanying drawings wherein for the 35 purpose of illustration is shown a preferred embodiment of my invention and wherein like reference characters designate like parts throughout.

In the drawings:

40 Figure 1 is a front elevation of a lock constructed in accordance with my invention, the cover plate of the locking part being removed;

Figure 2 is a section on the line 2—2 of 45 Figure 1;

Figure 3 is a section on the line 3—3 of Figure 1; and

Figure 4 is a detail view showing the mounting of the seal receiving elements.

50 Referring now more particularly to the drawings, the numeral 10 indicates a plate

adapted for attachment either to the door 11 or body 12 of the car. The plate has formed thereon an outstanding flange 13 substantially rectangular in form and one side wall 55 of which coincides or practically coincides with one edge of the plate 10. The flange at this side wall thereof is cut away, as indicated at 14, to afford a space through which, as hereinafter more fully will appear, 60 the bolt is entered. The plate 10 has formed therein a pair of sockets 15 and 16 which align with similar sockets 17 and 18 formed in a cover plate 19, which cover plate is attached to the flanges by riveting, as indicated at 20, and combines with the plate 10 and flange 13 to form a housing to which access is had through the opening or space 14 formed in the flange.

The numeral 21 designates a latch member comprising a bar having formed upon one end thereof lugs 22 for engagement in the openings 16 and 18 of the plates 10 and 19 respectively, and upon the opposite end with a shoulder 23 for a purpose presently 75 to appear. The numeral 24 designates a rotatable key operated part which is rotatably mounted in the sockets 15 and 17 of the plates 10 and 19 and which has formed therein a bore 25 within which are located key 80 engaging ports 26. This bore aligns with an opening 27 formed through the plate 19 at the base of the socket and through which an operating key 28 for coaction with the locking parts may be inserted. The locking part 85 24 has secured thereto a lever arm 29 which is provided with a flat angular extension 30 so spaced that when the locking part is in the locking position it engages flatly against the flange 13 at its inner face. The free end 90 of this angular arm 30 is connected by a link 31 with the latch member 21 so that upon rotation of the locking part, the latch may be swung to move the shoulder 23 thereof out of alignment with the opening formed 95 at 14. The latch bar 21 is normally held with the shoulder 23 thereof in alignment with this opening by means of a spring 32 secured at one end to the inner face of the flange 13 and bearing at its opposite end 100 upon the free end of the latch bar.

The plate 10 may be secured to the sur-

face to which it is applied in any desired manner, being preferably secured as by riveting at 33, and has attached thereto a member 34 provided with an apertured ear 35. The member 34 is preferably secured thereto by means of rivets extending through the member and plate and forms one receiving member of a pair adapted for the reception of a seal tape or wire. Secured to the 10 body or door as the case may be, is a locking bar plate 36, and this plate bears a second member 34 similar in construction to and coacting with the member 34 of the plate 10 when the door is in the closed position for 15 the reception of the tape.

The numeral 37 designates a locking bar embodying a head 38 of a size to permit its entrance through the opening 14 into the casing hereinbefore described, and having a 20 notch 39 in which the shoulder 23 engages. The bar 37 further includes a body portion 40 which is longitudinally slotted and which is separated from the head by an enlarged portion 41 limiting the entrance of the head 38 into the casing. Formed centrally of the plate 36 is an opening through which is directed a reduced extension 42 of a guide member 43 extending through the slot of the body 40 and having a head 44 overhanging 25 the face of the member 40 at the sides of the slot and preventing separation of the body from the plate 36. This extension is riveted upon the under side of the plate 36 to hold the member firmly in position. 30 Further guide members are provided, as indicated at 45, each comprising a substantially L-shaped member having an extension 46 directed through openings formed in the plate at the sides of the body portion 40 and riveted upon the under side of the plate. The angle portions of the L's overlie the upper face of the body 40 and abut the side faces thereof, thereby preventing either 35 transverse displacement or vertical displacement of this body. As shown in the drawings, the guides 45 are arranged in pairs and limit the movement of the locking bar 37 in opposite directions, the movement being limited in one direction by engagement 40 of one pair of members 45 with the enlargement 41 between the head 38 and body 40 and in the opposite direction by outstanding shoulders 47 formed upon the opposite extremity of the body. The body 40 45 has secured thereto an outstanding member 48 adapted to be engaged by the hand for shifting the same.

In the operation of my device when the door is closed the seal may be placed through 50 the apertured ears of the members 34 and the door left unlocked if so desired. When it is desired to lock the door, this may be accomplished by shifting the locking bar 37 to move the head 38 thereof into the casing 55 where the shoulder 23 will engage in the

notch 39 and lock the head against withdrawal until the key 28 is employed to release the same. It is preferred that the spring 32 be made of sufficient strength to hold the locking lever 21 against movement 70 by the locking bar 37 when no greater weight is urged thereagainst than the weight of the locking bar so that in event the locking bar is left in extended position when the door is closed it will not automatically 75 lock, thereby preventing the necessity of having a key at hand at all times when it is desired to close the door at intervals and is unnecessary to lock the same.

Many changes being possible in the construction of the lock as hereinbefore set forth without in any manner departing from the spirit of my invention, I do not limit myself to such specific structure except as hereinafter claimed.

I claim:

1. In a lock of the type described, a casing having an opening affording access thereto, opposed walls of the casing having formed therein aligned sockets, a lever provided at one end upon opposite sides thereof with hub portions adapted to engage in said sockets and provided upon its free end with a locking bar engaging shoulder, a spring normally urging the free end of said lever in one direction, a rotatable locking part, a lever carried by the locking part and having a portion flatly engaging a side wall of the casing to limit the rotation thereof in one direction, and a link pivoted to the lever of the locking part and to the first named lever.

2. In a device of the type described a casing having an opening affording access thereto through which a locking bar may be introduced to the casing, the locking bar having a notch, pairs of aligned sockets formed in opposed walls of the casing, a lever provided at one end upon opposite sides thereof with lugs rotatably engaging in one pair of said sockets, the free end of the lever being provided with a shoulder adapted to engage the notch of the locking bar, a spring urging said free end toward the locking bar to maintain said shoulder in engagement in said notch, a rotatable locking part mounted in the remaining pair of sockets, a lever secured to the locking part and having an angular portion flatly abutting one side wall of the casing when said shoulder is engaged in said notch, and a link pivoted to the first named lever.

3. In combination, a locking bar having a body portion provided at opposite ends thereof with enlargements forming stops and upon one end with a locking head adapted for engagement with a lock, a plate, pairs of L-shaped guide members attached to said plate and each having one portion thereof slidably embracing the side of the

body of the locking bar and a second portion thereof slidably embracing the face of the locking bar remote from the plate, the body of said locking bar being provided with a slot, a headed member directed through the slot of the locking bar and the plate and slidably abutting the upper face of the locking bar, said member being rivet-

ed upon the opposite side of the plate from the locking bar.

In testimony whereof I hereunto affix my signature.

CHARLES A. SCHMITT.
